United States Patent Office.

CHARLES BISHOP, OF TRUMBULL, CONNECTICUT.

Letters Patent No. 79,193, dated June 23, 1868.

IMPROVEMENT IN SHEARS.

The Schedule referred to in these Letters Patent and making part of the same.

TO ALL WHOM IT MAY CONCERN:

Be it known that I, CHARLES BISHOP, of Trumbull, in the county of Fairfield, and State of Connecticut, have invented a new and improved Joint for Shears, &c.; and I do hereby declare the following, when taken in connection with the accompanying drawings, and the letters of reference marked thereon, to be a full, clear, and exact description of the same, and which said drawings constitute part of this specification, and represent, in—

Figure 1, an inside view of one blade,

Figure 2 an inside view of the other blade, and in

Figure 3 a transverse section through the pivot.

This invention relates to an improvement in common shears, the object being to make a more perfect joint than can be done by the common pivot, and the invention consists in forming a circular flange upon one blade and a corresponding recess in the other, so that the two fitting together form the bearing for the two blades, while the screw or rivet, which passes through the two, has only to hold the two blades together, being by this construction entirely relieved from all strain.

In order to the clear understanding of my invention, I will fully describe the same as illustrated in the accompanying drawings.

A is the one blade, constructed with the finger-handle B, in the usual manner; C the other blade, with the thumb-handle D corresponding to the blade A, as in shears of common construction. a is a central hole, in which is usually inserted the pivot. Upon the one blade C, I form a raised flange, d, centrally around the hole a, and so as to leave a shoulder upon the inside of the flange, as seen in figs. 2 and 3. In the other blade A, I form a recess, f, corresponding to the flange d upon the blade C, so that the flange will set into the recess in the blade A, when the two are placed together, as seen in fig. 3; then, through the hole in each blade, I pass a rivet or screw, i, to screw the two blades together in the usual manner; and the shears are complete, and by this construction the bearing is made so large that there is much less wear upon the joint, and the blades are consequently held firmer and longer in their proper relative position to each other.

I do not broadly claim forming a disk upon one blade and a corresponding recess on the other blade, as this may be seen in the patent granted to T. J. Sloane, September 23, 1842.

Having fully described my invention, what I claim as new and useful, and desire to secure by Letters Patent, is—

Shears, the joint of which is constructed in the manner described; that is to say, the one blade constructed with a circular flange, d, the internal diameter of which is less than the rivet or screw, the other blade with a recess corresponding to the said flange d, and so that a portion of the recessed blade will enter, fill, and fit the space within the circular flange on the other blade, and through the centre of which a screw or rivet, i, is placed, to secure the two blades together, substantially in the manner and for the purpose set forth.

CHARLES BISHOP.
